DUMP CAR

Alfred C. Schmohl, Beaver Falls, Pa., assignor to
 Pressed Steel Car Company, Inc., Pittsburgh,
 Pa., a corporation of Pennsylvania

Application September 28, 1938, Serial No. 232,130

2 Claims. (Cl. 105—275)

The present invention pertains generally to dump cars of small capacity which are manually tilted and righted. The invention pertains specifically to an improved body tilting bearing and an improved locking device for the body.

Cars of this type are used for various industrial purposes and are usually manually propelled as well as manually operated. Such cars are frequently built with capacities of 40 cu. ft. and 10 more. The usual practice is to hinge one end wall of the body so that the lading can be readily discharged when the body is tilted.

Because of the relatively large capacities and the manual means employed to tilt the car body, 15 it becomes necessary to provide a body bearing which not only supports the car in stable equilibrium during movement of the car but one which can be easily moved by the operator from a position of stable equilibrium to tilted position.

20 These cars are often used in operations where it is advantageous to discharge the lading at times over the end of the underframe and at other times over the side of the underframe. The use of a hinged wall as a door for these cars makes 25 necessary locking means which not only retain the body in position during movement of the car but will retain the door in closed position until the operator is ready to discharge the lading.

An object of the present invention is to provide 30 a body bearing which supports the body in normal position and is easily moved to bring the body into tilted position.

Another object of the invention is to combine such bearing with means for bringing the body 35 into position for selective discharge of lading over the end or side of the car underframe.

A further object of the invention is to provide 40 a body and door lock to control the door during movements of the car or body until such time as the operator desires to release the lading.

In the drawings forming part of this specification, Fig. 1 shows in side elevation a car equipped with the invention; Fig. 2 shows an end elevation of the car; Fig. 3 shows in plan the body supporting bearing and turntable; Fig. 4 shows an end elevation of said bearing and turntable; and Figs. 45 5 and 6 show the various positions of the bearing as the body moves from normal to tilted position; Fig. 7 shows a section through the bearing on 50 lines 7—7 of Fig. 3; Fig. 8 shows an enlarged view of the various positions of the door lock when the locking means is securing the body and door in position, when the door is held locked and the body released and when the door is released.

Referring now in detail to the drawings wherein like reference characters refer to like parts, reference character 1 indicates a conventional underframe including spaced sills supported on wheeled axles 2 and a body 3 tiltably supported 5 on said underframe. One end wall of the body is constituted as a gate 4 having a top hinge connection to the body at the side walls 5 thereof.

The body 3 being supported upon the underframe for both rotary and tilting movement, rotary movement is provided by a turntable comprising a base 6 having apertures 7 therein for reception of suitable fastening members to secure the base to the underframe. A circular track 8 is provided on said base for reception of rotatable 15 supporting members, such as balls 9 and a cover plate such as 10 is supported by said balls. The base 6 has an upwardly extending hollow central portion 11 engaging within an aperture 12 of the cover plate to position the cover plate and suitable means may be inserted through portion 11 to secure together the turntable base and cover. 20

To support the body upon said turntable and provide tilting movement, lugs 13 are disposed upon opposite sides of the turntable cover 10 and 25 provided with oppositely disposed portions 14 adjacent the base thereof. Secured beneath the body are suitable body bearings comprising webs 15 disposed adjacent each lug 13, said webs having a top flange 16 for attachment to the car body and a bottom flange 17 engaging the portion 14 of the turntable cover 10. Flange 17 is preferably extended upwardly at the sides of web 15 to reinforce the said web. The flange 17 at the base of web 15 has a flat central portion to 30 provide support for the body in stable equilibrium and a curved end portion to provide a rocker upon which the body rolls during initial dumping movement. Each web 15 has an aperture 18 therein disposed above and outwardly of the flat 35 portion of flange 17, as shown in Fig. 5 of the drawings. Each lug 13 has an aperture 19 registering with aperture 18 and elongated downwardly therefrom and away from said flat portion of lug 13. The relation of the elongated 40 aperture 19 and the flat portion of flange 17 is such that as the body bearing rolls on the curved portion of flange 17, the aperture in web 15 moves into register with the lower end of aperture 19. Inserted through the registering apertures 18 and 45 19 are bearing pins 20 provided with suitable means such as cotter pins to retain the bearing pins in position.

Upon reference to Figs. 1 and 5 of the drawings it will be observed that the body supporting bear- 50 55

ings are disposed beneath the body 3 to bring the flat portion of flange 17 of the bearing beneath the center of gravity of the body as indicated by lines X—X. Preferably the major portion of the weight of both loaded and empty body is so disposed that the body will normally tend to be unbalanced and tip toward the rigid end of the car. To maintain the equilibrium of the car an upwardly extending portion 21 is provided upon the turntable cover 10 between the body bearings and for engagement with the underside of the car body when in normal position.

Because of this normally unbalanced mounting of the car body, and particularly in the larger capacity cars, considerable strain could be imposed upon the turntable cover plate lug 21. To relieve this I prefer to place additional supports such as 23 beneath the rigid end of the body as shown in Figs. 1 and 2 of the drawings.

20 A locking device for the body end wall door 4 comprises a shaft 35 disposed beneath the floor of body 3 and journaled in end plate 24 and brackets 28 and 28^a. One end of shaft 35 has an arm 36 adapted to overlie the door 4 and engage bearing plate 29 thereon. The other end of shaft 35 extends through end plate 24 to receive an operating handle 25 secured in position by nut 26. Handle 25 has a depending portion 27 terminating in a curved tip for engagement with pin 34 mounted in body support 23. At each side of the rigid end of the body are handholds 32 and handle 25 moves between same. A locking link 33 is mounted on one handhold 32 for engagement with handle 25. A suitably shaped bar 36 retains handle 25 in its various positions between handholds 32.

Three positions of locking lever 25 are shown in Fig. 2 of the drawings and correspond to the three positions of arm 36 illustrated in Fig. 8 of the drawings. With the lever 25 in position shown by full lines on Fig. 2, the arm 36 is shown by full lines in Fig. 8, the body 3 and door 4 are both locked in position as shown by full lines on Fig. 1. Upon movement of lever 25 of Fig. 2 to the right into intermediate position indicated by reference character 25^a the body is released for rotary movement upon the turntable but the door 4 is still held in locked position by arm 36 which has moved to position 36^a. After lever 25 is released from position 25^a and moved to position 25^b, arm 36 is correspondingly moved to position 36^b and door 4 is released for opening.

Referring again to Figs. 1, 2, 5 and 6 of the drawings, the body in Fig. 1 is locked in position 55 for transportation of lading after reaching the dumping point if end dumping is to be effected, the lever 25 is moved to either position as shown by reference character 25^a or 25^b and the operator tilts the car body. During its initial tilting movement the body and associated bearing rocks on web 17 and portion 14 of the turntable during which the bearing moves from position shown in Fig. 5 to that shown by full lines on Fig. 6 and pin 20 engages the lower portion of slot 19 of lug 13. Thereafter the bearing pivots on pin 20 in slot 19 of lug 13 until the body reaches fully dumped position where it rests on bearing plate 31 of the underframe. In this latter position of the body, lever 25 can then be moved to position 70 25^b, if not already in this position, and door 4 will open to release the lading.

In cases where it is desired to discharge lading to the sides of the car, lever 25 is again moved into the position indicated as 25^a and the body is rotated to bring door 4 to the desired position at

the side of the underframe 1. It will be observed upon reference to Fig. 2 of the drawings that the body can be rotated 90° or 270° to bring door 4 to either side of the underframe and with lever 25 in the position indicated by 25^a the door 4 is retained in locked position during this movement. Before rotation of the body, the operator may find it necessary to rock the car slightly on bearing 15 and turntable portion 14 to free the body from support 23 so as to prevent interference therewith. Thereafter upon the body reaching the desired position and lever 25 being moved to position 25^b the lading will be discharged.

After discharge of the lading the body may be 15 easily returned to normal position and locked again for reloading since during the initial return movement of the body it is pivoted upon pin 20 until web 17 of the bearing 15 again engages the turntable at 14.

From the foregoing description it becomes apparent that the car rocks on its bearings during initial dumping, thereby requiring little effort and after acquiring momentum is pivoted upon pin 20. Thus, considerable less effort is required 25 to dump the body than would be used were the body moved solely about a fixed pivot and there is less longitudinal movement of the body relative to the underframe than where the body rocks upon the turntable for the entire dumping 30 movement. Also, by use of the pivot a steeper dumping angle of the body is obtainable with a body disposed closer to the track than in designs using a rocker bearing for the entire movement, 35 thereby resulting in a more stable car.

Having thus described the invention what I claim as new and desire to secure by Letters Patent is:

1. A combination turntable and bearing support for a dump vehicle comprising a turntable base, a turntable cover supported on said base, upwardly extending bearing lugs spaced adjacent opposite sides of said turntable cover, an elongated aperture in each of said lugs above said cover each aperture being inclined downwardly 45 and outwardly toward the base of said lug, a vehicle body supporting bearing disposed adjacent each said bearing lug, each said body supporting bearing having a suitably shaped top portion for engaging the vehicle body and a bottom portion engaging the turntable cover, each said bottom portion curving upwardly at its junction with one body supporting bearing side wall to form a rocker shaped surface upon which the body turns in initial dumping movement, an 55 aperture in each said body bearing portion, a bearing pin substantially filling each said aperture and normally registering with the inclined lug aperture in spaced relation to the bottom thereof, said bearing pin registering with the 60 bottom of said inclined lug aperture after the body supporting bearing rotates on its rocker shaped portion and providing a pivotal support for the body supporting bearing on the bearing lug.

2. In a dump vehicle of the character described, in combination, an underframe, a turntable having a base secured in rigid relation to the underframe and provided with a rotatable top cover, bearing lugs secured to said top cover 70 and extending upwardly therefrom, a body supporting bearing having an upper portion connected to the body and a bottom portion supported on said turntable cover adjacent each said bearing lug, each said body supporting bearing 75

bottom portion including a rocker shaped surface curving upwardly from said turntable cover, a support for said body united with said bearing cover and extending upwardly thereof between 5 and rearwardly of said bearing lugs, an aperture in each said body supporting bearing and adjacent lug above said body bearing curved bottom portion and a bearing pin within said apertures connecting each said bearing with the adjacent 10 lug, said lug aperture being elongated downwardly and outwardly away from said body supporting bearing aperture, said body supporting

bearings providing the sole support for the body during the initial dumping movement thereof and the said bearing pins thereafter registering with the bottoms of the lug apertures providing the sole support for the body during the remaining dumping movements of the body whereby the tilting support for the body is first a rolling contact of said rocker shaped bearing surfaces on the turntable cover and thereafter a pivotal support on said bearing pins in vertical spaced relation to the turntable cover. 10
